Patented July 5, 1927.

UNITED STATES PATENT OFFICE.

JOHN A. JOHNSON, OF NEW YORK, N. Y.

BOTTLE-CAPPING MACHINE.

Application filed February 25, 1925. Serial No. 11,496.

My invention relates to machines for applying friction caps of any diameter to bottles, jars or other container and it is my object to produce a machine in which the pressure, while sufficient to accomplish the result, will not rise high enough to break the container, which can be adjusted to cap containers of different heights, which will compensate for variations of the containers encountered in commercial operation and which will cap a container although the same may have been positioned on the table in such manner as to initially receive pressure on but a portion of the cap.

In the drawing Fig. 1 is a front view of my machine; Fig. 2 a side view thereof and Fig. 3 a sectional view of the feed table on the line 3—3 of Fig. 1.

The machine comprises a main frame 1 supporting a table frame 2 which may be raised or lowered by loosening the bolt 3 and turning the screw feed 4. This adjustment is used principally to align the table with the filling machine.

This table frame carries a plurality of rollers 5 and drums 6—6 at either end thereof, the upper surfaces of the drums and rollers alining. A belt 7 passes over the rollers and drums, a tensioning device 8 being provided to keep it taut.

Located over the table and on the main frame is a pressure applying head block 9 vertically adjustable by a feed screw 10. This block carries a pair of crank disks 11 and 12, each of which has a gear 13 (and 14) secured thereto and also carries a train of gears 15 which transmit motion from one crank disk to the other.

Suspended from the pins on the crank disks are a pair of links 16 and 17 whose lower ends are rigidly secured to a plate 18. A presser plate 19 is yieldingly secured to the plate 18 by pairs of studs 20 and 21, secured to the plate 19 and passing through the plate 18 with springs 22, 23 interposed between the plates. This permits the plate 19 to yield upwardly with respect to the plate 18.

To revolve the crank disks 11 and 12 a main drive shaft 24 is journaled on the machine. A bevel gear 25 on the shaft meshes with a bevel gear 26 which is journaled on the frame. A splined shaft 27 passes through the gear 26 and is free to slide therein but revolves therewith, the lower end passing through a bearing 28 on the head

block 9 and carries a bevel gear 29 which meshes with a bevel gear 30 on the crank disk 12.

As the shaft 24 is revolved it will revolve the shaft 27 and revolve the crank disks with their gear train transmitting the motion from one disk to the other. The sliding splined connection between the gear 26 and shaft 27 permits the head block to be raised or lowered without interfering with the transmission of power.

To drive the feed table belt a gear 31, secured to the gear 26 meshes with a gear 32 also journaled on the main frame. A splined shaft 33 passes slidably through the gear 32 and has its lower end in a bearing 34 on the table frame 2. A gear 35 on the shaft 33 meshes with a gear 36 on the drum 6. As the shaft 33 is revolved the drum 6 will drive the belt 7 and cause it to travel under the presser head and over the supporting rollers 5.

The speeds of the shafts 27 and 33 are so calculated that when the plate 19 is in its lowest position and in contact with a cap on a container it will be travelling laterally at the same speed as the belt 7.

The operation of the machine is as follows:—The table is set level with the filling machine to receive the filled containers. The sealing head is adjusted up or down so that the plate 19 will exert a driving, sealing pressure on the caps, which are loosely laid on the containers, as the capped containers pass under the head. As the loosely capped containers pass under the sealing head, which is moving up and down and laterally, due to the crank motion, the plate 19 forces the closures tightly onto the containers. The springs between the plates 18 and 19 permit the plate 19 to yield under pressure and prevent breakage of the containers. They also act as compensators for containers of slightly varying heights.

If a container is placed on the belt at such time as the plate 19 will not press on the entire surface of the closure the next stroke of the sealing head will engage the entire closure because the plate 19 is of sufficient length, and the speed of the belt is such that each closure must receive a full area pressure stroke before it has travelled from one side of the machine to the other.

I claim:—

1. A machine for affixing closures to containers comprising a frame, a pair of drums,

a gear secured to one of said drums, a belt running over said drums, a presser head over said belt, a pair of crank disks on said head, 5 crank pins thereon, links suspended from said pins, a presser plate rigidly secured to the lower ends of said links, means for moving said presser head vertically, a drive shaft journalled on said frame, a gear journalled on said frame, a shaft passing through said 10 gear and splined thereto, a gear on the lower end of the shaft engaging the drum gear, means for driving said journalled frame gear from the drive shaft and for rotating the crank disks in synchronism with the 15 splined shaft whereby the belt and presser plate will travel laterally at the same speed when the plate is in contact with a closure.

2. A machine for affixing closures to containers comprising a frame, a drive shaft 20 and a gear thereon on said frame, gears journalled to said frame one of which engages the drive shaft gear, a head block mounted

on said frame, a pair of crank disks on said block, a gear on one of said disks, means for transmitting motion from one disk to the 25 other, a shaft splined to the journalled gear engaging the shaft gear, a gear on the lower end of said shaft engaging the disk gear, 30 crank pins on said disks, links suspended from said pins, a presser plate rigidly secured to the lower ends of said links, a table frame under said presser plate, a pair of drums thereon, a belt on said drums, a gear on one of said drums, a second shaft splined to a journalled gear on the frame engaging 35 the gear on the first splined shaft, a gear on the lower end of the second shaft engaging the drum gear whereby the belt and presser plate are synchronously driven so that their lateral travel is the same while the presser 40 plate is in contact with a closure.

In testimony whereof I have affixed my signature.

JOHN A. JOHNSON.
